Primary Examiner — Stacia A Cadmus(74) *Attorney, Agent, or Firm* — Wood Herron & Evans LLP(57) **CLAIM**

The ornamental design for a wheel, as shown and described.

DESCRIPTION

FIG. 1 is a front left perspective view of a wheel for a vehicle according to the present invention;

FIG. 2 is a front view thereof; and,
FIG. 3 is a left side view thereof.

The broken lines show environmental structure and form no part of the claimed design.

1 Claim, 3 Drawing Sheets**FIG. 1**

FIG. 2

FIG. 3
